[57] CLAIM

The ornamental design for a frame for a paint roller, as
shown.

DESCRIPTION

FIG. 1 is a side elevational view of a frame for a paint
roller showing our new design;

FIG. 2 is a top plan view thereof;

FIG. 3 is an elevational view of the side opposite that
shown in FIG. 1;

FIG. 4 is a bottom plan view thereof;

FIG. 5 is an end elevational view as seen from the left of
FIG. 1; and

FIG. 6 is an elevational view of the opposite end
thereof.

FIG. 1

FIG. 2

FIG. 3

FIG. 4

FIG. 5
